NURSING BOTTLE

Christy N. Lestakis, Portland, Oreg.

Application March 23, 1949, Serial No. 82,997

5 Claims. (Cl. 215—11)

1

My invention relates to nursing bottles and provides one that a baby may learn to drink from.

My nursing bottle is illustrated in the accompanying drawings in which Fig. 1 is a vertical section thru the bottle, nipple, and nut; Fig. 2 is a plan view of the bottle; Fig. 3 is a plan view of a modification of the bottle; Fig. 4 is a vertical section on the line 4—4 of Fig. 3; Fig. 5 is a vertical section on the line 5—5 of Fig. 3; Fig. 6 is a vertical section thru a plain edge flared portion of a bottle; Fig. 7 is a vertical section showing a nipple constructed to slip over the flared portion of a bottle; and Fig. 8 is a vertical section showing another version of a nipple and flared top bottle.

Throughout the drawings and the specification similar numerals refer to similar parts.

The numeral 1 indicates a glass bottle of slightly tapered cross-section drawn in at the neck 2 to form an annular shoulder 3. The annular neck 2 is enlarged at 2A above the shoulder 3 to provide space for the rubber nipple 4 and the annular plastic nut 5 which is provided with an interior quarter thread 6 adapted to engage the exterior quarter thread 7 formed on the interior of the enlarged neck portion 2A of the neck 2. The nut 5 is counterbored to form an interior shoulder 8 adapted to come into contact with the outer annular shoulder 9 formed on the exterior surface 10A of the nipple 4 so that the bottom 10 of the nipple 4 may be brought into contact with the top surface of the shoulder 3 of the bottle 1 to form a leak-proof joint as the nut 5 is tightened. This tight joint should be made before the bottom of the nut 5 comes into contact with said shoulder 3. Above the enlarged neck portion 2A the neck is again flared out to approximately the diameter of the base 11 of the bottle 1. The annular flared portion 12 may terminate as shown in Fig. 6, or it may terminate in a lip or bead as shown in Figs. 1 to 5. The bead 13 helps direct milk to the deepest portion of the annular flared portion 12 as the bottle 1 is tilted to drinking position and breaks the flow-over as the bottle is lowered from drinking position. Figs. 3, 4, and 5 show the top surface 12A of the flared portion 12 concavely formed and slightly fluted, six flutes 14 being shown with the numeral 15 indicating the ridge 15 of a flute. The flutes 14 provide additional help toward directing the milk to the mouth of the drinker. Fig. 5 is a section thru the ridge 15. It is to be noted that these ridges 15 strengthen the overhanging flared por-

2

tion 12. The annular flared portion 12 naturally forms an undercut portion 16 which provides the necessary space for the baby's lower lip regardless of what side of the bottle he or she is drinking from.

Fig. 7 indicates that a nipple 4 may be designed to hook over a wide mouth bottle as well as over a small mouth bottle. In other words, a nipple 4 may be designed to hook over the undercut portion 16 of the flared annular portion 12.

Fig. 8 shows another modification of a nipple adapted for use with a wide mouth bottle. In this instance, the interior surface 17 of the milk-holding portion 18 of the bottle converges only slightly to form the restricted neck portion 2' and then flares outwardly to form the enlarged or intermediate neck portion 2A' and incidently the annular shoulder 3'. The annular flared portion 12 may terminate as previously described and shown or it may have other configuration without departing from the basic idea. The lower end 19 of the rubber nipple 4 is made cylindrical in form and of a diameter slightly larger than the diameter of the restricted neck 2' so that when it is shoved down into position, as a cork, it will be compressed at the neck 2' and expanded below and above said neck 2', thereby holding the nipple securely and tightly in place. The nipple 4 is flared above its lower cylindrical portion 19 to the contour of the top surface 12A of the flared portion 12 and terminates in an annular flange 20 which rests upon the top of the bottle 1 when the nipple is in place and extends beyond the flared portion 12 about $\frac{1}{8}$ " so that the perimeter of the flared portion 12 is kept from coming into contact with a table for instance when the bottle 1 is resting on its side. When it is desired to put the nipple 4 on the bottle 1 the flange 20 is held between the thumb and forefinger and set on the bottle the cylindrical portion 19 being guided and centered by the converging annular portion 12. Pressure is then applied to the top surface 20A of the annular flange 20 and the nipple pressed into place where it is held by the shoulder 2' which indents the soft cylindrical portion 19. To remove the nipple opposite sides of the annular flange 20 are pressed together and incidently the cylindrical portion 19 whereupon the nipple may be lifted from the bottle.

What I claim as new over the prior art in nursing bottles is set forth in the appended claims.

I claim:

1. A nursing bottle comprising a bottle formed

with an interior shoulder, an interior thread, and an annular flared neck portion, a nipple having an exterior annular shoulder, and a nut formed with an interior annular shoulder adapted to engage the nipple shoulder and a thread adapted to engage the bottle thread to bring the bottom of the nipple tight against the bottle shoulder.

2. In a nursing bottle in combination with a nipple and a nut provided with a thread and adapted to clamp the nipple to the bottle, a bottle formed with an intermediate neck portion to receive the nipple and nut within and provided with a thread to engage the nut thread, a smaller lower neck portion positioned to form an interior annular shoulder between said neck portions for the nipple to be clamped against and a larger upper neck portion flared outwardly.

3. In a nursing bottle in combination with a nipple and a nut provided with a thread and adapted to clamp the nipple to the bottle, a bottle formed with an intermediate neck portion to receive the nipple and nut within and provided with a thread to engage the nut thread, a smaller lower neck portion positioned to form an interior annular shoulder between said neck portions for the nipple to be clamped against and a larger upper neck portion concavely flared outwardly.

4. In a nursing bottle in combination with a nipple and a nut provided with a thread and adapted to clamp the nipple to the bottle, a bottle formed with an intermediate neck portion to receive the nipple and nut within and provided with a thread to engage the nut thread, a smaller

lower neck portion positioned to form an interior annular shoulder between said neck portions for the nipple to be clamped against and a larger upper neck portion concavely flared outwardly and having its top surface fluted.

5. In a nursing bottle in combination with a nipple and a nut provided with a thread and adapted to clamp the nipple to the bottle, a bottle formed with an intermediate neck portion to receive the nipple and nut within and provided with a thread to engage the nut thread, a smaller lower neck portion positioned to form an interior annular shoulder between said neck portions for the nipple to be clamped against and a larger upper neck portion flared outwardly and terminating in a beaded edge.
